CASTING LADLE

Adolphe Busche, Woodbridge, and John H. Jago,
 Fords, N. J., assignors to American Smelting
 and Refining Company, New York, N. Y., a cor-
 poration of New Jersey

Application May 8, 1937, Serial No. 141,434

3 Claims. (Cl. 22—79)

The present invention relates to the casting of copper wire bars, and relates, more specifically, to an improved mechanism for filling the mold in which the wire bars are cast.

5 When imperfections are present in the wire-bar castings, such imperfections persist throughout the wire-fabricating operations and are present in the finished wire.

In the casting of such wire bars it is the general practice to mount the molds on a suitable 10 conveyor mechanism, such as a casting wheel, whereby the molds are brought successively beneath the pouring ladle which receives the metal from the furnace, and which discharges the metal 15 into the molds. Each mold comprises a plurality of mold cavities or recesses in parallel alignment for the simultaneous casting of a plurality of wire bars, and, depending upon the construction or type of the casting wheel, the molds are 20 mounted with these mold cavities extending either radially or tangentially of the wheel.

In either case, the ladles employed for transferring the copper from the furnace to the molds are composed of a shell of cast iron provided with 25 a lining of refractory cement of sufficient or suitable thickness. The copper enters the ladle from the furnace and, upon suitable tilting of the ladle, flows therefrom into the wire bar molds which are coated with a suitable mold dressing usually 30 consisting essentially of bone-ash.

During pouring operations, especially where the molds are disposed tangentially of the periphery of the wheel, the ladle may have an overall length of several feet along which the copper 35 flows in transit to the pouring spout, the copper thereby becoming coated with a film of copper oxide due to contact of the copper with the air. This copper oxide wets the cement and causes 40 spalling of the same with the result that parts of the cement become mechanically separated from the ladle and entrapped in the casting; and also the bone-ash mold dressing is wetted by this copper oxide and some of it becomes included in the wire-bar castings. These inclusions must be 45 removed from the wire-bars before shipment thereof is made to the fabricator, and at times the handling and manipulation of the bars becomes uneconomical because of the chipping operations thereon required to eliminate these foreign inclusions.

50 Additionally, during the intervals between pours, there is the tendency of the copper to solidify in the ladle and in the pour openings, forming accretions or "skulls" which adhere to the cement lining of the ladle, the removal of such accretions usually pulling some of the cement along with them, with the consequence 55 that further amounts of the cement become loosened and are washed out into the molds upon the next pouring of the copper.

One object of the present invention is to provide a ladle construction wherein the molten copper is protected against contact with excessive amounts of air during pouring and wherein the formation of the above-mentioned accretions 60 and "skulls" is inhibited or avoided.

A further object of the invention is to provide a ladle which is adapted especially for use in casting wire bars where the wire-bar molds are disposed tangentially to the circumference of 10 the casting wheel upon which the molds are mounted, the said ladle being provided with laterally extending discharge spouts.

A still further object of the invention is to provide a ladle which comprises a metal delivery 15 member or launder having a heat-insulating cover sealed in place thereon, and in which discharge openings are round holes extending through a comparatively thick body of heat insulating material forming the spouts.

20 Further objects and advantages of the present invention will become apparent as the description proceeds, and the features of novelty will be pointed out specifically in the appended claims.

The invention will be understood more readily 25 by a reference to the accompanying drawing in which Fig. 1 is a perspective view of a wire bar mold with metal receiving portion in casting position relative to a ladle which employs the improved features of the present invention.

30 Fig. 2 is a plan view of a portion of the ladle.

Fig. 3 is a front elevation of the discharge portion of the ladle.

Fig. 4 is a sectional elevation taken on the line 4—4 of Fig. 3, looking in the direction of the 35 arrows.

Fig. 5 is a longitudinal sectional elevation, taken on the line 5—5 of Fig. 2.

Referring more particularly to the drawing, A represents a wire-bar mold which is adapted to 40 receive metal from a ladle B, into which copper enters from a suitable wire-bar furnace, not shown. The ladle B comprises a reservoir portion 6 and a discharge launder 8, which comprises a channel 9 communicating therewith, the 45 said launder being composed of a metal shell 10 lined with a refractory cement 12. A typical composition of this cement may be Portland cement, 2 parts by weight; building sand, 2 parts by weight; and fire-clay, 1 part by weight. A 50 baffle or bridge member 7 separates the launder 8 from the reservoir 6, a passage 11 beneath the bridge 7 being provided to allow for flow of metal between the reservoir and launder. The bridge 7 is suitably secured in place in the walls 55 of the channel 9. This passage 11 is provided by deepening the bottom 13 of the launder at the bridge sufficiently to maintain a suitable head of metal in the reservoir 6 which forms also a seal for the opening 11 below the bridge 7, preventing, 60

thereby, passage of air from the reservoir 6 into the launder 8.

The launder 8 is provided with a plurality (four, for example) of laterally-extending discharge spouts 16, formed by extending outwardly at suitable points, the shell 10 of the launder and building up the cement lining in these extensions to a sufficient thickness for efficient heat insulation. In order to form the discharge holes for the metal, a pipe of suitable diameter is inserted through the cement of these spouts before the cement becomes hardened until the pipes enter the launder trough 9 adjacent to the bottom 13 thereof, the pipes being given a downward slope 15 towards the launder channel 9. When the pipes have been inserted completely through the spouts, they are withdrawn, leaving the holes 18 surrounded by comparatively thick layers of heat insulation which prevents solidification of the 20 copper at the discharge points of the ladle, thereby avoiding the formation of the so-called "skulls" referred to above. These discharge holes or passages are of uniform diameter, for example, 1½ inches, and are disposed in the same horizontal 25 plane, there being provided as many such discharge spouts as there are wire-bar mold cavities in each mold.

As each mold A moves under the launder 8, the mold cavities 14 are directly beneath the respective discharge spouts, so that each spout will deliver a stream of metal to the mold cavity directly beneath it. The ladle is tilted by any well-known type of tilting mechanism, whereupon the molten copper flows beneath the bridge 7 into the launder 35 8 and through the discharge holes 18 to fill the molds. The discharge holes 18 being of the same dimension and being supplied with metal under the same head, and being in the same horizontal plane, there is provided a control of the 40 amount of copper being poured in a given time, thereby producing wire-bars of greater uniformity of weight.

A further feature of the present improved construction lies in the provision of a thick brick 45 cover which extends from the distal end of the launder to the bridge member 7. For holding this cover in place, the launder 8 is provided with a frame 20 along its top, which frame is formed, conveniently, of inverted L-shaped angle members 50 having their vertical leg embedded in the body of the launder, with their horizontal leg towards each other, these horizontal legs forming retaining flanges for holding the brick cover in position against the top of the launder. The 55 cover 22 is sealed air-tight, by means of a refractory seal 24, which may extend over the top of the cover.

This sealed cover construction has at least two important functions; that is to say, it prevents 60 heat losses with consequent building up of solid copper accretions along the walls of the launder-channel 9, during casting operations, and it also excludes air from contacting with the copper as it flows through the launder 8. It will be understood that the molten copper contained in the 65 reservoir 6 is protected from the air by a suitable layer of charcoal or the like in accordance with usual practice.

Access of air to the copper in the launder 8 is 70 inhibited also by the round or restricted discharge passages 18 and by the slope of the latter, which causes the molten copper to tend to seal these

discharge passages against admission of large amounts of air, which admission is also restricted by the fact that the interior of the launder is sealed by the bridge 7 with the body of metal therebeneath and by the air-tight cover 22.

Therefore, the launder becomes essentially a dead-air space through which the copper flows for pouring, and since there is substantial exclusion of fresh air from entering the launder, the formation of a copper oxide film on the copper is 10 obviated very substantially; also, because of the highly heat-insulating character of the construction, the formation of frozen copper accretions and/or "skulls" in the launder and discharge spouts is prevented, so that there results virtually 15 complete elimination of inclusion of cement in the cast bars, with the consequent very material reduction in the amount of chipping necessary to prepare the cast bars for shipment to the wire mill.

What is claimed is:

1. A ladle for use in casting copper wire-bars, which comprises a reservoir portion, and a launder portion extending from the reservoir portion over wire-bar molds as the latter are moved into 25 casting position, the said launder comprising a trough provided with a relatively thick layer of refractory heat-insulating material, a heat-insulating cover for the trough for covering the same along substantially the entire length thereof, a 30 plurality of discharge spouts extending laterally from the said trough and having discharge openings enclosed completely in a relatively thick body of heat-insulating material, a retaining frame for the cover extending along each side of the trough and engaging the cover to secure the same in position on the trough, and a refractory seal enclosing the cover along the lines of junction thereof with the said launder trough, thereby preventing formation of substantial amounts 35 of copper oxide during the pouring of the metal. 40

2. Apparatus for casting copper wire-bars comprising the combination with wire-bar molds having mold cavities disposed tangentially of the circumference of the mold, of a ladle having a launder portion extending over the molds and comprising discharge spouts extending laterally from the launder over the mold cavities for directing copper from the launder into the said cavities, and means for the launder and the 45 spout for protecting the copper against oxidation as it passes from the melting furnace to the molds.

3. Apparatus for casting copper wire-bars, comprising the combination with wire-bar molds, 50 of a ladle for pouring metal from a melting furnace into the said molds, the said ladle comprising a trough-like launder, a plurality of laterally disposed discharge spouts extending from the launder over the molds as the latter are moved 55 into casting position, an angle-frame extending along the sides of the launder on the top thereof, the said angle-frame having oppositely disposed horizontal legs, a cover inserted beneath the said legs and secured thereby to the top of the launder, and an air-excluding seal extending along the sides of the cover for preventing excess of air between the cover and the interior of the 60 launder.
